Application March 1, 1933, Serial No. 659,064
In Germany March 8, 1932

6 Claims. (Cl. 101—422)

It has already been proposed to provide devices which, by spraying the freshly printed sheets with liquid and subsequently solidifying paraffin, wax or the like, prevent smearing of the sheets on delivery.

The known spraying devices are either rigidly connected to the frame, or they are secured on the outside of the delivery table in such a manner that a spraying pistol is reciprocated crosswise to the direction in which the sheets fly.

In the spraying devices which are rigidly secured to the frame the sheets are sprayed while on the fly bands of the press, that is to say on their way to the delivery table. Thereby the whole of the fly mechanism for the sheets and other parts of the press are covered with spraying substance, which, in time, forms a hard crust. Parts of this crust are scraped off by the sheets that follow on and get into the pile of printed sheets. Other particles of the solidified crust break off from the continuously running bands and fall on the last delivered sheet. When the second side of the sheet is printed, such parts of the crust are forced into the type set and cause time wasting hold ups and useless printing.

Where a spraying pistol is disposed on the outer side of the delivery table and reciprocates crosswise to the direction in which the sheets fly, the cloud of spraying substance is blown into the press, which also gives rise to the troubles above referred to. In addition, the room required for the assistant working at the delivery table is unduly restricted, so that the checking of the printing which is continually carried out during delivery, the adjustment of the pile and later the removal of the pile is made very difficult. Especially the removal of the pile can only be effected with great difficulty and with utmost caution, due to the spraying device being disposed at the edge of the delivery table.

These defects may be removed by means of the improvements described in the following: A spraying device which is particularly suited for the present purpose is disclosed in my Patent No. 1,987,046.

In principle, the invention consists in this that the spraying device is disposed over the delivery table in such a manner as to reciprocate in the direction in which the sheets fly. For this purpose in two revolution machines the spraying device may be disposed on the reciprocating delivery trolley over the sheet carrying surface thereof. In stop cylinder machines the spraying device may be disposed on the delivery table so as to reciprocate in the direction in which the

sheets fly, and it may be reciprocated by a rod system driven for example by the fly rod or by the single revolution shaft.

In the accompanying drawings one form of the invention is shown by way of example.

Fig. 1 shows the delivery trolley in the position which it occupies shortly before the delivery of the sheet.

Fig. 2 shows the position of the delivery trolley wherein the sheet is delivered from the trolley to the delivery table and is sprayed during this operation.

Figs. 3, 4, 5 and 6 show two forms of construction by way of example of the arrangement of the spraying members for a stop cylinder press.

Fig. 3 shows the delivery mechanism of the press in the position occupied shortly before the delivery of the sheet. The spraying device is driven by the fly rod.

Fig. 4 shows the machine illustrated in Fig. 3 in a position, wherein the printed sheet is delivered on the delivery table and the delivery mechanism performs its return movement, the spraying members spraying the delivered printing sheet. Figure 4a illustrates a detail of the actuating lever for the spraying device. An improved actuating mechanism is disclosed in my aforementioned patent.

Figs. 5 and 6 illustrate the drive of the spraying device being taken off in a stop cylinder machine from the single revolution shaft, in two different positions.

Figs. 7, 8, 9 show a form of construction, wherein the spraying device is mounted on separate rails.

Fig. 7 shows a spraying device movable forward on two separate rails, in the position of rest, the spraying device being interconnected with a trolley carrying the fly sticks and running on two rails disposed below the upper rails.

Figs. 8 and 9 shows details of the device illustrated in Fig. 7, and especially the construction of the trolleys and their rails.

Referring to Figs. 1 and 2, in two revolution presses the spraying device is carried by side plates 1 which are fixed to racks 2 of the delivery trolley with screws 3.

Mounted at the upper part of the side plates 1, there is a spray pipe 5 provided with spraying members 4, the said spray pipe being provided on the outside with melting pots 6 for the spraying substance. Disposed in end pieces 7 there are control shafts 8 for actuating the spraying members 4, and secured fast to such control shafts there are levers 9 provided with rollers 10. The

cams 11 are adjustably mounted on side plates 14 of the two revolution press. The cams 11 are adjusted by means of screws 12 which extend through slots 13 made in the cams. The cams 11 are provided with sloping running up and running off surfaces for the rollers 10. The flier bands 15 carry the printed sheet 16. The sheet pile lies on the delivery table 18. The gears 19 are in engagement with the racks 2 of the delivery trolley, which at its front carries the band roller 20.

The operation is as follows:

The printed sheet 16 is carried by the flier bands 15 mounted on the flier rollers 20 from the printing cylinder over the pile 17. Gears 19 which are in engagement with racks 2 cause the delivery trolley to move backwards whereby the printed sheet 16 is delivered on the pile 17 on the delivery table 18.

20 During this backward movement of the delivery trolley the whole spraying device 5 which is rigidly secured to the delivery trolley by means of side plates 1, is moved therewith. By running up on the cams 11 (Fig. 2), the rollers 10 effect rocking 25 of lever 9 and control shaft 8, whereby the spraying members mounted on the spraying pipe 5 are opened, so that the sheet running off the flier roller 20 is sprayed. The spraying substance is fed from the melting pots 6 to the spraying pipe 30 5 and is indicated at 30.

In stop cylinder presses (Figs. 3 and 4) the spraying device is mounted in side bearings 21, which by means of a slide piece 22 are movably mounted in guide rails 23. The guide rails 23 are 35 mounted on the delivery table 18 parallel to the direction in which the sheets fly. In the upper part of the side bearings 21 is mounted the spraying pipe 5, which is provided with spraying members 4, the pipe being connected outside with melting pots 6. For setting the spraying members 4 into operation control shafts 8 are mounted in end pieces 7, and mounted on the shafts 8 there are levers 9 having rollers 10. The cams 11 are 40 adjustably mounted on the guide rails 23 by means 45 of screws 12, which reach through slots 13 made in the cams 11. Secured to the fly rod 25 there are levers 24 which are hinged to rods 26 hingedly connected to glide pieces 22. The well known fly sticks 27 carry the printed sheet 16 (Fig. 3). 50 The pile 17 is on the delivery table 18. The fly rod 25 is rockably mounted in eyes 28 of the frame side plates 29.

The operation is as follows: The printed sheet is taken off the printing cylinder by means of the fly sticks 27 secured to the fly rod 25 and are placed on the pile 17 on the delivery table 18. During this operation the spraying device 5 is moved forward under the action of lever 24, rods 26 and gliding pieces 22 towards the edge 188 of 60 the delivery table, whereby the fly sticks are given free access to the delivery table 18 for delivering the printed sheet 16 thereon. Following the forward movement the fly rod is reversed and thereby the whole spraying device is moved backwards. During this movement towards the rear of the spraying device the rollers 10, by mounting the cams 11, effect the rocking of lever 9 and the control lever 8, whereby the spraying members 4 mounted on the spraying pipe 5 are opened, 65 so that the spraying of the printed sheet 16 delivered on the pile 17 by the fly sticks 27 (Fig. 4) is performed, and this is done at the moment when the sheet is already lying on the pile 17, or in Fig. 2, is about to be laid on the pile 17. The spray is directed towards the outer edge 188 of

the pile 17. Movable parts of the press are therefore not sprayed at all.

The lever 9 may be constructed as illustrated in Fig. 4a. It consists of a main lever 9a fixedly attached to shaft 8. An auxiliary lever 9b is pivotally connected to the free end of lever 9a. The former has at its rear end an extension 9c which engages a boss 9d on the main lever 9a so that the auxiliary lever is free to swing independent of the main lever in one direction. The lever 9b carries at its free end a roller 9e which is adapted to engage cam 11, while a spring 9f tends to maintain the extension 9c against the boss 9d. When the spraying device moves to the left the lever 9a is revolved in a counterclockwise direction to open the spraying nozzles, while in the other direction the link of the two levers is broken, as indicated in dotted lines and the spraying nozzles remain closed.

In Figs. 5 and 6 a form of construction is shown, wherein the drive of the spraying device in stop cylinder presses is taken off the single revolution shaft. This enables the spraying device to be so controlled that during the printing operation it reciprocates at half the speed of the fly only, so that the control members of the spraying device are not strained so much, the additional strain of the fly drive, which in many cases cannot be imposed at all, is avoided.

A single revolution shaft 102 is mounted in the usual manner in the frame 101 and carries a gear 103 which engages a gear 104. The gear 104 and a crank 105 are mounted fast on a pivot 106. A link 107 is hinged to the crank 105 and a rocking lever 112. A rocking shaft 113, disposed beneath the path of the fly sticks 27 and carrying the rocking lever 112 and on both sides arms 124, is rotatably mounted in flange bearings 115 secured to the frame side plates 29 by means of screws. The arms 124 are pivotally connected to connecting rods 26 which are hinged to gliding pieces 22. Such gliding pieces 22 are slidably mounted in guide rails 23, which are secured to the delivery table 18 parallel to the direction in which the sheets fly. The fly sticks 27 are secured to the fly rod 25a which is rotatably mounted in the frame side plates 29. A side bearing 21 secured to the sliding pieces 22 carries the spraying device 5.

The operation is as follows: The rotary movement of the crank 105 caused by the continuous rotation of the single revolution shaft 102 and the gears 103 and 104 effects the rising and sinking of link 107, whereby the shaft 113 is rocked to and fro once by means of the lever 112 during one cycle, that is to say during one revolution of the single revolution shaft 102. This motion is transmitted by means of the arms 124 and the connecting rods 26 to the gliding pieces 22, which are sliding in their guide rails to and fro in the horizontal direction, the side bearing 21 which carry the spraying device 5 being moved to and fro by positive action.

The movement of the fly rod 25a with the fly sticks 27 is effected in such a manner that a cam 66 is disposed in a well known manner, which, by means of a rocking lever effects the rotation and the stoppage of the fly sticks.

Figure 5 illustrates one mode for accomplishing the desired results. Attached to the shaft 102 70 is an eccentric 103a having a connecting rod 103b which in turn is coupled to a shaft 103c by means of a crank 103d. Upon rotation of the shaft 102 the shaft 103c is thus caused to oscillate preferably through an angle of about 90° while the shaft 75

102 completes a revolution. The shaft 102^c also has attached thereto a gear 103^c which meshes with a smaller gear 103^a which latter in turn is attached to the shaft 25^a of the fly rod. Hence the 5 fly rod is oscillated through the required angle of approximately 180° while shaft 102 makes one revolution.

During the standstill of the fly rod 25^a the spraying device is already moved by means of the 10 crank drive described above from the position shown in Fig. 5 forward, that is to say towards the outer edge 188 of the delivery table 18. When the spraying device moves over half of its stroke the rotary movement of the fly rod 25^a moves with 15 double the speed of the spraying device, so that the forward dead centre of the spraying device 5 and of the fly sticks 27 is reached at the same time. The return movement of both devices commences simultaneously (Fig. 6) so that the fly 20 sticks 27 have nearly reached their rearward dead centre when the spraying device sprayed half of the delivered sheet 16. During the further return movement of the spraying device 5 the fly sticks are substantially at a standstill. The 25 spraying is started when during the return movement of the spraying device 5 the roller lever 9, 10 controlling the valves of the spraying device 5 runs over the cam 11.

The spraying device 5 may be sometimes of 30 considerable weight and it is preferable to run it on separate rails. A form of construction embodying this feature is shown in Figs. 7, 8 and 9.

There are provided running rails 41 securely attached to the frame 42 of the press on both 35 sides of the delivery table 18 in the direction in which the sheets fly. Secured to both ends of the rail 41 there are latches 43 extending vertically upwards and fixed by means of screws 44. Fixed to the upper extremities of the latches 43 by 40 means of screws 46 there are rails 45, so that an upper track 45 and a lower track 41 is provided. Secured to the rails 45 there are cams 47 which are made with slots 48 wherethrough pass bolts 49 which may be screwed into the rail 45 so that the cams 47 are adjustable. The ends of the 45 spraying device 5 are mounted on two trolleys 50 carrying rollers 51 which may travel along the upper rail 45. Extending laterally from the trolleys 50 there is a control lever 9 with control 50 rollers 10 for the spraying device 5. Extending vertically downwards from the trolleys 50 there are rods 52 having a slot 53. A pivot 54 engages in slot 53, the said pivot being secured to a trolley 55 running on the lower rail 41.

The trolleys 55 carry rollers 56 which run on 55 the lower rails 41. Mounted on the trolleys 55 there are pull rods 58 rotatable round pivots 57, the said rods being hinged to arms 24 secured to the rocking lever 25 mounted in the frame side plates 42.

60 Mounted in the trolleys 55 (Fig. 7) is the fly rod 60 to which are secured the fly sticks 27. Mounted in the side frames 42 there is a rocking shaft 62 provided with take off members 61 and a fly roller shaft 64 provided with fly rollers 63.

65 The operation is as follows: The rocking shaft 25 is rocked to and fro in a well known manner, whereby a horizontal reciprocating movement of the trolleys 55 running on the rails 41 is obtained by means of the arms 24 and the rods 58. The fly sticks 27 which are secured to the fly rod 60 mounted on the trolleys 55 are thereby also reciprocated. In their rear dead centre position they receive the printed sheet in a well known manner from the fly bands 15 and during their

forward movement carry same over the pile 17 on the delivery table 18. During the next rearward movement of the trolley 55 the take off members are turned up with the rocking shaft 62 in a well known manner, so that the printed sheet 5 16 is prevented from returning during the rearward movement of the trolley 55, it is taken off from the fly sticks 27 and is placed on the pile 17, in a manner similar to that shown in Fig. 2. This method of delivering the sheet is known. 10

While the trolleys with the fly sticks 27 reach their forward dead centre position on the rails 41, the trolleys 50 connected to trolleys 55 by means of the rods or links 52 are equally moved forward in a positive manner, the said trolleys 50 15 carrying the spraying device 5 and running on the rails 45.

During the rearward movement of the trolleys 55 the spraying device also moves backwards. The control rollers 10 mounted on the control 20 levers 9 run up on the cams 47 and cause the opening of the spraying nozzles provided on the spraying device 5, whereby the printed sheet 16 which has just been delivered is covered with a 25 cloud of liquid paraffin or the like protecting the fresh printing. The spray cone of the spray nozzles is directed towards the outer edge 188 of the delivery table 18.

There are printing machines wherein the lower rails for the trolley 55 is not disposed horizontally as shown in Fig. 7, but so as to slope from the front towards the outer edge of the delivery table. Such a construction is shown in Figs. 8 and 9. In this case the upper guide rail for the trolley 50 of the spraying device 5 is disposed 35 horizontally, and the latches 43 are shorter on the press side than on the front side. Due to the slots 53 or lost motion provided in the rods 52 the trolley 55 is able to adjust itself to the varying distances of the trolley 50, as will be seen in Figs. 8 and 9. 40

I claim:

1. The combination with a printing press, having a delivery table, of mechanism for delivering sheets from the press and depositing them in succession on said table with the printed faces 45 up, a sprayer mounted to move toward and from the delivery end of the press and over the delivered sheets, and means for causing a spray of anti-offset liquid to be emitted from said sprayer onto the printed surfaces of the sheets in a direction away from the delivery end of the press as said sprayer moves toward the press.

2. The combination with a printing press, having a delivery table, of mechanism for delivering sheets from the press and depositing them in succession on said table with the printed faces up, a sprayer mounted to move toward and from the delivery end of the press and over the delivered sheets, and means actuated by the reciprocation of the sprayer for causing a spray of anti-offset 55 liquid to be emitted from said sprayer onto the printed surfaces of the sheets in a direction away from the delivery end of the press as said sprayer moves toward the press.

3. The combination with a printing press, having a delivery table, of reciprocating mechanism for delivering sheets from the press and depositing them in succession on said table with the printed faces up, a sprayer mounted to move toward and from the delivery end of the press and over the delivered sheets, mechanism connecting said delivery mechanism and said sprayer so that they will reciprocate in synchronism, and means for causing a spray of anti-offset liquid to be emitted from said sprayer onto the printed surfaces 70 of the sheets.

faces of the sheets in a direction away from the delivery end of the press as said sprayer moves toward the press.

4. The combination with a printing press, having a delivery table, of oscillatory means for delivering sheets from the press and depositing them in succession on said table with the printed faces up, a sprayer mounted to move toward and from the delivery end of the press and over the delivered sheets, means to move said sprayer, and means actuated by the reciprocation of the sprayer for causing a spray of anti-offset liquid to be emitted from said sprayer onto the printed surfaces of the sheets in a direction away from the delivery end of the press as said sprayer moves toward the press.

5. The combination with a printing press, having a delivery table, of oscillatory means for delivering sheets from the press and depositing them in succession on said table with the printed faces up, a sprayer mounted to move toward and from the delivery end of the press and over the delivered sheets, means to move said sprayer in

synchronism and with said oscillatory means, and means actuated by the reciprocation of the sprayer for causing a spray of anti-offset liquid to be emitted from said sprayer onto the printed surfaces of the sheets in a direction away from the delivery end of the press as that sprayer moves toward the press. 5

6. The combination with a press, having a delivery table and adapted for printing and delivering sheets in succession on said table with the printed faces up, of mechanism for coating said printed faces with quick drying anti-offset liquid, said mechanism comprising spray producing means mounted to move toward and from the delivery end of the press parallel with the table above the sheets to be coated, mechanism to reciprocate said spray producing means, and mechanism for causing a spray of anti-offset liquid to be projected from said means in a direction away from the delivery end of the press and onto the sheets on the table as the spraying means moves over the sheets in one direction only. 10 15 20

KURT BERGNER.
